(57) **CLAIM**

The ornamental design for a cabling connector, as shown and described.

DESCRIPTION

The claimed cabling connector is used to connect electrical elements of a heated garment.

FIG. 1 is a perspective view of a cabling connector showing my new design;

FIG. 2 is a first side view thereof;

FIG. 3 is a second side view thereof;

FIG. 4 is a top view thereof;

FIG. 5 is a bottom view thereof;

FIG. 6 is a third side view thereof; and,

FIG. 7 is a fourth side view thereof.

The broken lines are for illustrative purposes only and form no part of the claimed design.
